UNITED STATES PATENT OFFICE.

CHARLES WILLARD NELSON, OF KANSAS CITY, MISSOURI, ASSIGNOR TO THE SOVEREIGN GRAND LODGE OF THE INDEPENDENT ORDER OF ODD FELLOWS, A CORPORATION OF MARYLAND.

DESIGN FOR A BADGE.

40,265.

Specification for Design. Patented Sept. 21, 1909.

Application filed July 24, 1909. Serial No. 509,464. Term of patent 14 years.

To all whom it may concern:

Be it known that I, CHARLES WILLARD NELSON, a citizen of the United States, residing at Kansas City, in the State of Missouri, have invented a new, original, and ornamental Design for Badges, of which the following is a specification, reference being had to the accompanying drawing, forming part thereof.

The figure is the front view of a badge, showing my new design.

I claim:

The ornamental design for a badge, as shown.

CHARLES WILLARD NELSON.

Witnesses:

E. A. HOSIER,
Wm. M. SMITH.
